PIVOT CONNECTION FOR LEVERS

Filed April 13 1923

Inventor
Harry C. Schaper
By F. R. Tomvaloffsky.

UNITED STATES PATENT OFFICE.

HARRY C. SCHAPER, OF ST. LOUIS, MISSOURI, ASSIGNOR TO THE WEIGHT-O-GRAF COMPANY, OF ST. LOUIS, MISSOURI, A CORPORATION OF MISSOURI.

PIVOT CONNECTION FOR LEVERS.

Original application filed October 13, 1921, Serial No. 507,492. Divided and this application filed April 13, 1923. Serial No. 631,902.

My invention relates to new and useful improvement in pivot connections for levers and the present application is a division of an application for patent on weight indicating scales filed by me October 13, 1921, Serial Number 507,492.

The objects of the present invention are to provide a simple and efficient bearing for the interengaging knives of a pair of cooperating levers.

Further objects of the invention are to provide a single bearing member having bearing faces on its opposite sides for engaging the oppositely disposed knife edges of the levers and to provide means for retaining the bearing block in operative relation with one of said levers.

With these and other objects in view my invention consists in certain novel features of construction and arrangement of parts hereinafter more fully described and claimed, and illustrated in the accompanying drawings, in which—

Figure 1 is a longitudinal cross section through the base of a scale in which are housed the interengaged load actuated levers.

Figure 2 is a fragmental plan view of the interengaged levers.

Figure 3 is a vertical cross section taken on line 3—3 of Figure 2.

Figure 4 is a vertical cross section taken on line 4—4 of Figure 3.

Figure 5 is a detail perspective view of the retaining plate.

Figure 6 is a detail perspective view of the bearing member.

Referring by numerals to the accompanying drawings, 10 indicates a box-shaped base which houses the load receiving lever system of a scale. Projecting inwardly from the side walls of said base are cylindrical portions 11 in which are mounted bearings 12. The upper ends of these bearings carry bearing blocks 14 having upwardly presented V-shaped grooves in which are arranged the knife edges of pivot members 15. These pivot members are fixed in the ends of a pair of spaced parallel bars 16 and 17, transversely disposed in the base 10. The bar 16 which occupies the forward end of the base 10 has inwardly projecting arms 16^a to the extremities of which are fixed upwardly presented knife-edge pivot members 18. The bar 17, which is located toward

the rear of the base 10, has inwardly projecting arms 17^a and the extremities thereof are provided with upwardly presented pivot members similar to members 18.

A bearing block 19 carried by the upper end of a loop 20 is provided with a downwardly presented V-shaped groove which is designed to be engaged by the knife edge of the pivot member 18 and support the loops 20 on the arms 16^a and 17^a. These loops 65 straddle the ends of said arms, and the lower ends of said loops are designed to receive the hooked upper ends of short rods 21. The lower ends of said rods have adjustably mounted thereon semi-spherical members 22, 70 which are received in bearings formed in the undersides of the stirrups 24 and support the same in position. The upper ends of the stirrups 24 are secured to, or formed integral with a spider 25 which extends upwardly through a suitable opening formed in the upper end of base 10. This spider is provided at its corners, and preferably in vertical alignment with pivot connections 19 and 20, with bosses 26 having suitable 80 sockets for receiving the pins 27 of a platform 28. Thus the platform 28, which is arranged above the spider 25 and is spaced from and surrounds the upper end of the base 10, is supported in position and 85 suspended from the arms 16^a and 17^a by the loops 20 and the stirrups 24.

A lever 29 is fixed at its forward end to the bar 16 and extends rearwardly in the base 10 and its extreme rear end carries a 90 nose portion 30, which is designed to be engaged by a loop 31 fixed to the lower end of a steel yard rod 32 the upper end of which is connected to suitable weight indicating mechanism. A lever 34 extends inwardly and forwardly from the bar 17 and is preferably bifurcated at 34 to clear the lever 29, and the forward end of said lever extends upwardly through a slot 35 formed in the lever 29, and is provided with a horizontally disposed portion 36 which occupies a position above the lever 29, as shown in Figures 1 and 3. This horizontal portion has arranged therein a block 37, in which is fixed a downwardly presented knife edge 100 member 38 which is adapted to have bearing in the upwardly presented V-shaped groove of a bearing member 39.

A knife-edge pivot member 40 is fixed to the lever 29 transversely in the slot 35, and 110

its upwardly presented knife-edge has a bearing in the downwardly presented V-shaped groove of bearing the member 39. The oppositely disposed V-shaped grooves 5 of the member 39 are vertically aligned with each other so that the knife-edge members 38 and 40 of the levers 34 and 29, respectively, are maintained in proper alignment with each other as shown in Figure 3.

19 The provision of bearing the block 39 permits the use of a plurality of pivot points between the interengaged levers so that the operating strain is distributed over a number of pivot members instead of being concentrated at a single point thereby insuring the sensitive operation of the device and prolonging the life of the knife-edge members. The block 37 is preferably held in position in the horizontal portion 36 of the 20 lever 34 by a pin 41 which passes through said block, and is seated in the portion 36. This pin permits slight movement of the block 37, thus permitting the knife-edge member 38 to automatically adjust itself relative to the bearing block 39, and the knife-edge member 40. To prevent the displacement and loss of bearing member 39, when the levers are disassembled, a pair of 25 retaining plates 42 are secured to the ends of the block 37, and have at their lower ends inwardly projecting lateral portions 44 which when the lever 34 is removed from its position on the lever 29 are adapted to engage the projections 45 formed on the 30 block 39 and retain the member in operative relation with the knife-edge member 38.

The plates 42 are of sufficient length so that when the lever 34 occupies operative position on the lever 29, and the member 39 is 40 engaged by the knife-edge members 38 and 40, the projections 44 formed on the lower ends of the plates 42 are spaced a sufficient distance below the projections 45 on the member 39 to provide operating clearance 45 therebetween, and not interfere with the operation of the member 39.

I claim:

1. In a scale, a pivot connection for interengaged levers, comprising a pair of opposed knife-edge members, a self adjusting connection between one of said members and its lever, and a bearing block interposed between the knife edges, said bearing block being provided with seats adapted to receive 50 the respective knife edges.

2. In a scale, a pivot connection for interengaged levers, comprising a pair of opposed knife-edge members, a self adjusting connection between one of said members and its levers including a pivot pin, and a bearing block interposed between the knife edges, said bearing block being provided with seats adapted to receive the respective knife edges.

3. In a scale, a pivot connection for inter-

engaged levers, comprising a pair of opposed knife-edge members, a self adjusting connection between one of said members and its levers including a block and a pivot pin seated in the lever and passing through said block, and a bearing block interposed between the knife edges, said bearing block being provided with seats adapted to receive the respective knife edges.

4. In a scale, a pivot connection for interengaged levers, comprising a pair of opposed knife-edge members, a self adjusting connection between one of said members and its levers including a channel in the end of the lever and a block pivotally supported in said channel, and a bearing block interposed between the knife edges, said bearing block being provided with seats adapted to receive the respective knife edges.

5. In a pivot device for levers, a pair of opposed knife-edge members, and a bearing block having oppositely disposed V-shaped grooves for interengaging said members.

6. In a pivot device for levers, a pair of opposed knife-edge members, and a bearing block provided on its opposite faces with vertically aligned V-shaped grooves for engaging said knife-edge members.

7. In a pivot device for levers, a pair of opposed knife-edge members, a grooved bearing block for interengaging said members and maintaining the fulcrum thereof in vertical plane, and means for retaining said block in operative relation with one of said knife-edge members.

8. In a pivot device for levers, the combination with a pair of levers, of a bearing member provided in its oppositely disposed faces with V-shaped grooves for providing knife-edge pivot engagements with said levers, and means for retaining said bearing member in operative relation with one of said levers.

9. In a device of the class described, the combination with a pair of levers, of oppositely disposed knife-edge pivot members arranged on said levers in vertical alignment with each other, and a single double-grooved bearing block for interengaging said knife-edge pivot members.

10. In a device of the class described, a pair of oppositely disposed levers each having a knife-edge pivot at its outer end, a bearing block provided in its upper and lower faces with V-shaped grooves, a knife-edge pivot member carried by one of said levers and engaging the lower end of said grooves, and a knife-edge pivot member carried by the free end of the other end of said levers and engaging the upper end of said grooves.

In testimony whereof I hereunto affix my signature this 30th day of March, 1923.

HARRY C. SCHAPER.
